ARTICLE SUPPORTING RACK FOR PLATING

Albert Pearson, Western Springs, Ill., assignor to
 Western Electric Company, Incorporated, New
 York, N. Y., a corporation of New York

Application October 3, 1936, Serial No. 103,872

3 Claims. (Cl. 204—5)

This invention relates to article supporting racks, and more particularly to racks for plating sheet metal.

Certain articles require a localized coating and it is often desirable to restrict the covered areas, particularly when costly coating materials such as gold or other noble metals are employed. In some cases it is desirable to coat one side of a metal sheet and subsequently to form the composite sheet into the article.

An object of this invention is to provide an improved method and rack for use in the application of a localized coating on sheet material.

In accordance with one embodiment of the invention, a rack is provided for supporting a metal strip in a plating apparatus and localizing the deposit of metal on one face thereof. The rack comprises a continuous surface having an oval section on which the strip is wound spirally and clamped to prevent contact between the electrolyte and the under surface of the strip. Plating current is conducted to the strip through a contact bar along the top of the rack.

A complete understanding of the invention may be had from the following detailed description taken in conjunction with the appended drawing in which the single figure is a perspective view of a plating rack embodying the invention.

For convenience and economy a plating rack embodying the invention is adapted for use in a conventional electroplating apparatus in which the rack is suspended from a bus bar 10 in an electrolyte (not shown).

As shown in the drawing, a supporting frame made of wood, fibre, or other insulating material comprises a main rectangular vertical frame member 11 which has a rounded bottom portion 12. A plurality of cross members or arms extend horizontally and symmetrically from the two faces of the main member at right angles thereto. A central cross arm 13 is supported at the approximate middle of each face of the main member. Two upper cross arms 14 and two lower cross arms 15 mounted near the respective ends 45 of the main member are relatively shorter than the central arms so that the ends of the cross arms and main member describe an approximate oval.

Mounted along the full length of the top of the main frame member is a half round rod or bar 16 of brass, copper, or other conducting material. The rod is secured with the flat surface of its semi-circular cross section in contact with the frame member and its diameter projecting symmetrically beyond the two faces of the member.

A bracket 17 is welded to each end of the rod and fastened to the main frame member with screws.

A continuous sheet 18 of fibre, rubber or other insulating material, equal in width to the length of the conductor rod is mounted around the outer ends of the frame cross arms and secured thereto with countersunk screws 19. The two ends of the sheet abut against the portions of the rod projecting beyond the face of the main frame member and are anchored securely with screws (not shown) to the main member. The projecting portions of the half round rod are made equal to the thickness of the sheet to insure a smooth continuous surface at the junctures between these members. At the bottom of the rack, the sheet nests against the rounded portion of the main frame member and the rod and sheet thus collectively provide a continuous, smooth surface for receiving the strip material.

To each end of the half round rod a formed arm 20 of brass, copper or other conducting material is secured by welding, brazing, or other suitable method, such as threading the arm into the rod to provide a good electrical contact for conducting plating current to the rod. The two arms extend upwards and are each provided with a hook 21 for engaging the bus bar of the plating apparatus and a handle 22 for convenient transportation of the rack.

At the upper left corner of the rack just below the conductor rod is a clamp 23 threaded in the main frame member and provided with an enlarged head of rubber or other non-conducting material. A similar clamp 24 is mounted on the rear right face of the rack.

In loading the rack one end of the metal strip 25 is anchored under the left hand clamp. The strip is then wound spirally on the surface of the rack and the conductor rod under sufficient tension to insure close contact between the underside of the strip and the rack surface. The terminating end of the strip is fastened securely with the right hand clamp to hold the strip and rack in proper relationship. Circulation of the electrolyte against the inner surface of the strip is prevented by contact with the rack surface and the deposit of metal on that area is accordingly prevented.

Plating current is introduced to the strip through contact with the half round rod, which is connected to the bus bar through the supporting arms. Introduction of current to the uniformly spaced intervals of the strip in contact

with the rod facilitates the electrodeposition of a uniform coating on the strip surface.

In the plating operation, vertically arranged anodes (not shown) are positioned on opposite sides of the rack and the metal strip on the rack serves as a cathode. In general, a series of alternate anodes and cathodes are employed with anodes at each end of the series.

The dimensions of the rack details are determined largely by the composition and size of the material to be coated. Compact and easily handled racks are employed for brass strip .003" thick which conforms readily to the surface contour of the rack. In constructing the rack, careful consideration is directed to the frame members which are preferably constructed to form the strip supporting surface into an approximately oval section so that all portions of the strip will be in close contact with the convex surface of the rack. For relatively thick material it may be necessary to form the rack more nearly cylindrical in shape to insure continuous contact between the strip and rack surface. However, a rack having an elongated axis is preferred because this construction presents the strip more uniformly to the plating anode which assists in control of coating thickness and also permits a greater number of racks to be placed in a tank of given length.

The surface of the rack can be made of hard rubber or phenol fibre and in some cases may be faced with soft rubber, depending on the size and composition of the strip material. For plating thin brass strip, hard rubber approximately $\frac{1}{8}$ " thick was used satisfactorily and the thin strip was retained in sufficiently close contact with the rack surface without difficulty. For thicker strip or material which does not distort easily a soft rubber facing into which the material can be imbedded may be required. Durable, non-conducting materials are employed for the frame, strip supporting sheet and clamps to prevent the deposit of metal on the rack members and to reduce maintenance and repair costs.

A rack of this general description is also suitable for supporting strip material during coating processes other than electroplating, such as paint

or varnish spraying, in cases where it is desirable to restrict the coating to one side of the strip.

Other modifications of the specific structure described herein can be made to accommodate various requirements, and it is to be understood that the invention is limited only by the scope of the appended claims.

What is claimed is:

1. A plating rack for metal strip, comprising a frame of non-conducting material, an elongated member made of conducting material mounted on the frame, a sheet of insulating material mounted on the frame with its ends abutting against the conducting member for receiving the metal strip, a clamp mounted on the frame for securing one end of the strip, a second clamp on the frame for engaging the other end of the strip and holding the strip in close contact with the insulating sheet and the conducting member, and means for conducting plating current to the conducting member. 10

2. A plating rack for metal strip, comprising a frame of non-conducting material having a main vertical member and a plurality of cross members extending therefrom, a bar of conducting material secured to the top of the vertical member, a continuous sheet of insulating material secured to the end of the frame cross members with its ends abutting the conducting bar, and an arm of conducting material extending from the 25 bar for conducting plating current thereto.

3. A rack for plating metal strip, comprising a frame having a central member and a plurality of cross arms projecting therefrom, a bar of conducting material having a semi-circular cross-section secured to the top of the central frame member with portions of the bar diameter extending beyond both faces of the frame member, a continuous sheet of insulating material secured to the ends of the frame cross arms with its 35 ends abutting the projecting portions of the conductor bar for supporting the strip, a formed arm secured to the bar for conducting plating current thereto, and a plurality of clamps for securing the strip to the supporting surface of the rack. 40
